United States Patent Office

Des. 205,657
Patented Sept. 6, 1966

205,657

CHILD'S CHAIR

Marco Zanuso, Via Laveno 6, Milan, Italy

Filed Feb. 24, 1965, Ser. No. 83,964

Term of patent 7 years

(Cl. D15—1)

FIG.1

FIG.2

FIG.3

FIG.4

FIG.5

FIG. 1 is a front elevational view of a child's chair, showing my new design;

FIG. 2 is a side elevational view thereof;

FIG. 3 is a top plan view thereof;

FIG. 4 is a rear elevational view thereof, and

FIG. 5 is a perspective view of the chair.

The side not shown is the same in appearance as the side illustrated in FIG. 2.

I claim:

The ornamental design for a child's chair, as shown and described.
